REMOTE-CONTROL SYSTEM FOR RADIO RECEIVERS AND THE LIKE

Robert L. Harvey, Princeton, N. J., assignor to
 Radio Corporation of America, a corporation
 of Delaware

Application August 31, 1949, Serial No. 113,305

1 Claim. (Cl. 343—228)

1

This invention relates to remote control systems, particularly to the wireless type of remote control system for controlling the tuning operation of distant apparatus such as radio receivers or the like.

The problem of remotely controlling apparatus with a flexible type of control unit such as one based on a wireless, that is a radio type, linkage from a remote control unit to the apparatus, has previously been met by incorporating a complete radio transmitter in the remote control unit and connecting the apparatus to be controlled to an auxiliary radio receiver control assembly actuated by the transmitter. Such a system is shown for example in U. S. Patent No. 2,297,618, granted September 29, 1942, to Grimes et al.

The operation of a remote control unit including a transmitter is subject to several difficulties however. The transmitter must have a source of power and this is supplied either through connecting wires from the commercial power lines, or by means of self-contained batteries. External connecting wires are quite cumbersome to handle and greatly reduce the versatility of the system as well as its usefulness. Self-contained batteries, on the other hand, have a limited life even when the control unit is not used, and require periodic servicing of the unit, as well as the provision of special construction features to permit ready servicing.

Further difficulties with batteries are that they are relatively expensive, under certain conditions such as high ambient temperatures they become discharged quite rapidly even on open circuit, and they require the taking of special precautions to prevent discharged batteries from damaging the unit by reason of the escape of battery chemicals.

Another disadvantage of the transmitter type of remote control unit is that it necessarily includes relatively fragile components such as vacuum tubes that can be easily broken or put out of commission by rough handling.

It is accordingly an object of the present invention to provide an improved wireless type of remote control system in which a remote control unit does not require batteries or a special power supply connection.

A further object of the invention is the provision of an improved remote control system and remote control unit in which no delicate components such as vacuum tubes are present in the unit.

Prior remote control systems, such as the one shown in the above-identified patent, in order to

2

provide selectable types of remote control operations i. e. to change the signal output intensity as well as to change the tuning of a radio receiver, have resorted to the use of interacting controls that have to be simultaneously actuated to suitably vary the remote control signals. This introduces some awkwardness in the manipulation of the controls and necessitates some degree of manual dexterity and attention.

10 An additional object of the present invention accordingly is the provision of an improved remote control unit in which no control elements have to be simultaneously manipulated, and the control elements are actuated one at a time.

15 Still further objects of the present invention include the provision of an improved radio wave operated remote control system in which interference from undesired radio waves is substantially impossible even though the undesired waves are of substantially the same frequency as the control waves.

The above as well as other objects of the invention will be more readily understood from the following description of exemplifications thereof, reference being had to the accompanying drawings wherein:

Figure 1 is a block diagram illustrating some of the general principles of a remote control system embodying the present invention;

30 Figure 2 is a similar block diagram of a different form of remote control system according to the invention;

Figure 3 is a diagrammatic showing of an improved remote control unit exemplifying one phase of the invention, for use with a distant apparatus to be controlled; and

35 Figure 4 is a schematic illustration, with parts in block diagram form, of one form of control assembly incorporating the invention that cooperates with a remote unit such as that of Figure 3.

40 In the remote control system of the invention, a remote control unit has a radio wave reflecting component together with a control element for changing the reflection characteristics of the component. An auxiliary control transmitter and receiver are connected to the apparatus to be controlled and provide radio waves for reflection by the remote unit as well as sensing elements that respond to changes in the wave reflection to effect control operations on the apparatus.

45 The sensing elements are connected to compare the waves that are transmitted with those that are reflected so that reflection changes are readily detected. Frequency modulation of the transmitted waves will so distinguish them from other

ambient waves of substantially the same frequency that there will be very little likelihood that these other waves will interfere with the wave comparison.

The remote control unit of the invention avoids the use of delicate circuit components by having a reflection-changing arrangement mechanically pulsed or vibrated. A pulser and vibrator, or different vibrators are operated separately or in sequence to provide different kinds of reflection signals from which the sensing unit derives different types of control operations.

Figure 1 of the drawings shows an embodiment of the invention in which an apparatus 10 that is to be remotely controlled is connected to a controller 12 actuated by waves generated at a high frequency generator 14. The generated waves are transmitted by a radiator shown as a dipole antenna 16, reflected by a remote control unit 18 and received at a collector 20, shown as another dipole antenna.

A comparing circuit represented by block 22 is supplied with the waves received at collector 20 and also receives some waves directly from the generator 14, as indicated by the leads 24. Inasmuch as the reflected waves and the directly supplied waves are carried in different paths, they will have different characteristics. Thus unless the paths are of exactly the same length electrically, the two waves will be differently phased, the comparator 22 being arranged to detect the phase difference.

Where frequency modulated waves are supplied by generator 14, the phase difference will be accompanied by a difference in frequency, so that the comparator may simply be a frequency comparing device such as a heterodyne stage having an output or beat frequency circuit connected to selectively receive those waves corresponding in frequency to the frequency change undergone by the generated waves during the phase separation interval of the two paths.

The comparator 22 supplies comparison-indicating waves to a senser 26 that forms part of a control assembly including the controller 12. Here variations in the reflected waves are responded to and control signals derived for controlling the apparatus 10. Thus by pulsing the reflection characteristics of the remote control unit 18, the comparator 22 will supply output waves correspondingly pulsed or modulated, and the senser 26 may merely be a detector stage connected to demodulate the pulses and supply the demodulated pulses to the controller 12. Power amplification may be included in the senser 26, the controller 12 or in both of these sections to assist in the control operation by raising the intensity of the control pulses to the level at which the desired controls are readily actuated.

In Figure 1, the remote control unit 18 includes a reflecting structure shown as a dipole antenna 28, connected to an antenna circuit changer 30. This circuit changer is connected to vary the reflection characteristics of the antenna 28 by simply changing the circuit to which it is connected. As one type of suitable construction the changer 30 is nothing more than two antenna leads and a shorting switch connected to directly short the leads as desired. By actuating the shorting operation according to a predetermined code or sequence, different kinds of control functions can be produced.

To improve the phase separation between the reflected waves and the waves directly carried by circuit 24, a delay network can be included

to delay the waves passed either through the circuit 24 or the transmission and reflection path. This is especially advantageous where the remote unit 18 is separated from the apparatus

10 by relatively small distances such as those available in homes or auditoriums. With such small distances the time required for waves to make the round trip to the remote unit and back to the comparator 22 is so short as to yield a phase displacement difficult to detect and less than can be readily supplied by a delay network. By increasing the phase separation, a greater portion of a frequency modulation swing can be made available for comparison, thereby simplifying the comparison circuits as well as the wave generation.

The particular form of delay network used is not a part of the present invention. Any convenient arrangement can be used, such as the one described in "Principles of Radio" by the members of the staff of the Radar School, Massachusetts Institute of Technology, second edition, published 1946 by McGraw Hill Book Company, Inc., New York, N. Y. pages 2-98. Another convenient type of delay network is one that depends on the inductive coupling of circuits and makes use of the 90 degree phase lag accompanying the inductive transfer of waves.

Where the delay is applied to the directly supplied waves passing through circuit 24, the antennas 16, 20 should be so disposed that there is very little energy transfer directly between them. This can be arranged by orienting them till a null or minimum wave pickup appears at antenna 20 with the generator 14 in operation, or by placing between the antennas a shield that prevents direct transfer of waves but permits waves to travel between the individual antennas and the remote control unit 18.

Although separate transmitting and receiving antennas 16, 20 are shown in Figure 1, their functions can be combined in a single antenna. Figure 2 shows such an embodiment of the invention. Here a frequency modulated generator 114 supplies the waves to be transmitted, through a delay network 117 to an antenna 116. Radiated waves are reflected from a remote control unit 118 including an antenna 128, antenna circuit 129, and a set of individual circuit changers 131, 132, and 133. The reflected waves 118 are received by antenna 116. On the generator side of the delay network 117, a direct path 124 is provided from the generator 114 to a senser 126 connected to respond to changes in the circuit 129 of the remote control unit 118. In this way the reflected waves are given a further delay through the same delay network 117 through which they were delayed in the transmission.

In the form of the invention shown in Figure 2, each of the circuit changers 131, 132, 133 is arranged to provide distinguishable effects on the reflection characteristics of the unit for controlling a signal receiver 110. As one example of distinguishable controls, the changers are adjusted to periodically short out the antenna circuit 129 at different predetermined frequencies or sequences. Each changer may be used for a different control purpose such as controlling the energization, tuning and output intensity of the receiver 110. A distinguishing selector 119 receives the signals supplied by the senser 126 and selectively supplies them to corresponding individual controllers 111, 113, and 115. These are individually connected to apply the desired control action to the receiver 110.

The controlling actions in the construction of Figure 2 may be of the type such as are explained in detail in the above-identified Grimes et al. patent.

Figure 3 shows the essential details of one type of remote control unit exemplifying the invention. An antenna 228 has a pair of leads 234 connected in parallel to a pulse-type shorting switch 236 and, through a sequence control switch 238 to a vibrating-type shorting switch 240. Connected to operate the pulse-type switch 236 is a coded pulsing or dialing apparatus 250 similar to that used with conventional dial type telephones. The vibrating type switch 240 is operated by a plucking or striking mechanism 260 similar to conventional piano movements.

The pulsing mechanism shown at 260 includes a disc 251 pivotally mounted for rotation around its center, and having a plurality of selector openings 252 distributed circularly around it. The individual openings are identified by the letters A to J and are of a size that easily receive the finger tip of a remote control operator. A fixed stop bar 253 is placed in the rotatory path of the finger that is engaged in an opening 252.

The disc 251 is biased in a counterclockwise direction as by the coil spring 249 and normally held in ready position as by the engagement of an arm 255 carried by the disc with a fixed stop pin 254. The disc is free to turn in the clockwise direction however. A damper mechanism 256 shown as including a step-up gear train 248 and an air vane governor 247, is connected to the disc to make its counterclockwise rotation by the spring 249 more uniform, and, if desired, more limited in speed.

A cam 246, rotates with the dial disc 251 and cooperates with a cam follower shown as a lever 257 pivoted at 258. A nose portion 245 of the lever 257 is held against the cam 246 as by the centering spring 244. A pulse pin 243 carried by the lever 257 is engaged by a movable blade 237 of switch 236, normally biased away from a fixed contact 235 of the switch. The cam 246 has a number of cam lobes 242 positioned to correspond with the individual finger openings 252 which may be identified by suitable indicia.

To operate the pulse or dial mechanism, it is only necessary to place the finger in a selected finger opening, then rotate the dial around in clockwise direction with the finger in the opening till the finger engages the stop bar 253, and then withdraw the finger. The clockwise rotation of the cam lobes 242 moves the follower nose 245 downwardly in an intermittent manner, tilting the pulse pin 243 upwardly away from the switch blade 237. Switch 236 accordingly remains open. Upon release of the dial disc 251, it is carried back in counterclockwise direction by spring 249 to the rest position shown, but this time the follower nose 245 is intermittently moved upwardly by the successive cam lobes 242, causing the pulse pin 243 to repeatedly bring movable switch blade 237 against the cooperating contact 235. A succession of pulsed short-circuiting of antenna leads 234 is thereby produced.

The plucking or striking mechanism 260 is of the type shown in U. S. Patent No. 2,220,088 granted November 5, 1940, to T. L. Dowey. It includes a ratchet wheel pivoted to an L-shaped control lever 263 at 265, the lever itself being pivoted at 267 and carrying an operating button or head 269. The lever 263 is biased in clockwise direction against a stop member 271 by spring 273, and in this position, a vibratable

blade 242 of switch 240 has its free end 244 engaged between adjacent teeth 246 of the ratchet wheel. A spring blade 275 fixed at 277 also has its free end 279 engaged between other teeth 246. A stop 281 prevents the spring blade 275 from moving away from its operative range of positions.

As is more completely explained in the Dowey patent, depressing the head or button 269 moves the ratchet wheel away from switch arm 242 around pivot 267 and also rotates the wheel around its own pivot 265 causing a tooth 246 to pluck the arm 242 and set it into vibration. A fixed contact 243 cooperates with the vibrating arm 242 to cause periodic closing of switch 240 at a relatively high frequency so long as the arm is vibrating. Upon release of the button 269, the lever 263 is carried back against stop 271 bringing the ratchet wheel 261 against the blade 242, arresting the vibrations and cocking the mechanism for the next operation.

The relatively slow pulses produced at switch 236 are readily distinguished from the rapid closing of switch 240 which may have a repetition frequency 5 or more times as high. For simplifying the operation the shorting switches 236, 240 are arranged for preventing simultaneous action. Arm 255 of the dial mechanism coacts either the normally open switch 238 and functions to close this switch only when the dial is in its normal rest position shown. The switch 238 is accordingly open at all times during the dialing, thereby disconnecting vibrating switch 240 from at least one of the leads 234.

To operate the controls of Figure 3, the dial mechanism can be manipulated for one type of control action, such as the tuning shown in the Grimes et al. patent, or the vibrating mechanism operated for a different type of control action. Suitable response mechanism such as that shown in block form in Figure 2, is provided to distinguish the control signals. More than one vibrating mechanism can be used to provide control signals of different vibratory frequencies.

Figure 4 shows the essential details of a control assembly that can be connected with a radio signal receiver to operate it with a remote control unit of the type shown in Figure 3. A frequency modulated wave generator 314 of any convenient type, supplies modulated high frequency waves to a heterodyne circuit 322 which may be nothing more than a crystal mixing stage. A reflection-receiving antenna 320 supplies to the heterodyne circuit 322 waves reflected by the remote unit. The beat frequency output waves of the circuit 322 are amplified by amplifier 323 and changes in reflection are detected by detector 326 and supplied as pulses of electric current to the winding of a relay 301 having two sets of normally open contacts 302, 303.

The energization and deenergization of relay 301 controls the operation of a positioning tuning control member shown schematically as a reversible electric motor 305 having separate rotation direction controlling windings 306, 307 and auxiliary split commutator segments 308, 309. Relay 301 also controls the operation of an output intensity or volume control electric motor, the rotation direction control windings of which are shown at 370 and 372.

The operation of these motors is effected in the construction of Figure 4 in a manner similar to that shown in U. S. Patent No. 2,241,157, granted May 6, 1941, to W. T. Powell. A progressively moving or stepping switch 380 of the type

described in U. S. Patent No. 1,472,465 granted October 30, 1923, to Forsberg et al. together with an additional two-winding relay 390 are connected to provide the desired operation.

The stepping switch 380 is shown in the ready position and includes energizing windings 382 and two brushes or wipers 383, 384 connected to be progressively moved by the windings in clockwise steps across separate sets of stationary contacts 385, 386. A normally closed set of contacts 387 is also arranged to be opened each time the windings 382 are energized. Individual commutator contacts 388 are adjustably positioned to be engaged by the commutator segments 388, 389, and correspond in number to the desired number of remotely controllable tuning positions. The commutator contacts 388 are separately connected to the individual contacts of set 385. The first few contacts of the set 385 are left unconnected, while two contacts of the same set are separately connected to the reversing windings 370, 372. All the contacts of set 386, except the one engaged by brush 384 in the ready position shown, are connected to a movable contact 393 of relay 390.

The stepping switch is also arranged to advance its arms 383, 384 only upon the termination of an actuating pulse. Thus for example it may include a pawl and ratchet stepping mechanism connected so that the initiation of a pulse merely cocks the pawl against a bias spring while the cessation of the pulse permits the cocked pawl to advance the ratchet to the next step.

Relay 390 has a normal winding 391 and a slow release type of winding 392, both arranged to attract the movable switch contact 393 from its non-operated position against stationary contact 394 to an operated position against an opposed contact 395. The windings 391, 392 as well as winding 382, 386, 307, 370 and 372 are all energized by suitable alternating or direct current power supplies, the oppositely polarized terminals of which are shown diagrammatically by the circled plus and minus signs.

As shown in Figure 4, the tuning motor 305 is at the fifth remotely controlled tuning position, the fifth (counting clockwise) of the group of contacts 385 being connected to the commutator brush 388 opposite a gap between commutator segments 388 and 389. To shift the tuning to the fourth position, a sequence of eight pulses of reflection changing are effected. Eight current pulses are accordingly passed by the detector 326 through the windings of relay 301.

At each pulse contacts 302 and 303 close momentarily. Closing of contacts 302 completes an energizing circuit for the stepping switch windings 382 through the slow release windings 392, advancing the arms 383, 384 one step. Contacts 303 in closing establish an energizing circuit for the volume control windings 370, 372. At every step away from the ready position, arm 384 connects one power supply terminal to movable contact 393 which throughout the pulsing is held in its operated position against contact 395 by the slow release characteristic of the winding 392. In this operated position contacts 393, 395 prepare an energizing circuit for windings 391 and tuning motor 305 through arm 383, commutator segment brushes 388, and one of the direction controlling windings 386, 307. The relay windings 391 act as a holding device to maintain this circuit energized so long as it is completed, regardless of the cessation of control pulses in relay 301.

At the eighth pulse, arm 383 reaches the contact of set 385 connected to the fourth tuning brush 388. The tuning motor circuit is thereby closed through windings 306 causing the motor to turn the commutator segments in the clockwise direction as seen in Figure 4, until the gap between the segments is moved to the fourth brush 388, opening the energizing circuit and stopping further tuning.

10 Relay windings 391 thereupon become deenergized, and if a sufficient time has elapsed for slow release windings 392 to release, contact 393 returns to its non-operated position against contact 394 where it completes an energizing circuit for stepping switch windings 382 through contacts 387. These last contacts act as interruption contacts causing the stepping switch to step itself along to the ready position shown where the arm 384 is no longer connected to contact 393 and further operation ceases.

15 On the way up to the fourth brush 388, arm 383 stops momentarily at the volume control windings 370, 372, as well as the first, second and third tuning positions. Inasmuch as these pauses are of relatively short duration no significant control operation is produced.

20 The above tuning operation also applies to the other tuning positions which only differ in the number of steps involved.

25 30 For increasing the signal output intensity or volume, three remote control pulses are effected, followed by a series of remote control vibrations of higher frequency. The three pulses bring the arm 383 to the contact 385 connected to winding

35 370 of the volume control motor, in the same manner as the tuning. At the completion of the third pulse the relay 301 would be deenergized were it not for the succeeding vibrations which keep it energized so that its sets of contacts 302, 303 40 remain closed. The volume control motor is accordingly energized through contacts 303 and windings 370 until the vibrations are completed, permitting the contacts 303 to return to open position. After the slow release windings 392 45 permit contact 393 to return to non-operated position against contact 394, the stepping switch steps itself back to the ready position.

50 The first few contacts of set 385 may be left disconnected to prevent undesired operation in response to electrical noise, static or other interfering waves.

55 Decreasing the volume is accomplished in the same manner, windings 372 being energized instead of windings 370. The volume control motor may also be arranged to automatically shut off the controlled radio receiver at the lower limit of volume, as by conventional limit switches.

60 It will be noted that the control operations described in connection with Figure 4 are readily effected with a remote control unit of the type shown in Figure 3. The various openings C to J, inclusive, may have associated legends identifying the corresponding tuning positions, openings A and B being marked, respectively, "on—volume up" and "volume down—off."

65 A feature of the invention is that the volume control is readily effected in a simple manner. It is only necessary to dial A or B, and after releasing the dial 251 to press the vibration control button 269 till the desired change in volume is reached, after which the button is released. The completion of the pulsing occupies some time after the dial is released and the slow release of windings 392 permit more time to elapse before

the vibration is started, without interrupting the sequential control action.

The permissible manipulation time interval is increased readily if desired as by locating the volume control openings 252 at the I and J positions or at some positions between A and J.

The generator 314, amplifier 323 and detector 326 can be operated with electron discharge tubes that consume a minimum amount of power to limit the power drain of the control apparatus which may be continuously in operation. Vacuum tubes of the type having directly heated cathodes are suitable for this purpose. As pointed out above, the heterodyne circuit may function without a power supply, by using the well known crystal type mixers.

The generator 314 may have a vacuum tube oscillator modulated in frequency at a 60 or 120 cycle rate by a variable condenser vibrated directly by the commercially supplied alternating current power, so that the generator needs only one electron discharge device and uses very little power.

Although the remote control antennas have been shown as dipoles for use at very high radio frequencies, they can also be of other types such as loop antennas and thereby conveniently used with lower remote control frequencies, as low as 100 kilocycles per second, for example.

While several exemplifications of the invention have been indicated and described above, it will be apparent to those skilled in the art that other modifications may be made without departing from the scope of the invention as set forth in the appended claim.

What is claimed is:

In a remote control system the combination of a receiver to be controlled; a source of carrier oscillations, a delay network and a transmitting antenna connected in series in the order named; 40 a powerless remote control unit including a reflective antenna, a plurality of individual antenna

impedance changing circuits connected to said reflective antenna, and means for actuating each of said circuits so as to change the impedance of said reflective antenna in accordance with a predetermined sequence whereby the energy reflected from said reflective antenna varies in accordance with said sequence; antenna means adjacent said receiver for receiving said reflected waves; a sensing unit connected in series with 10 said delay network and said antenna means to detect remote circuit changes, a selector unit energized by the output from said sensing unit; said selector unit having a plurality of output circuits; control units connected to said receiver and adapted to vary the tuning and volume of said receiver; each of said control units being individually connected to one of said output circuits whereby the operation of said receiver is controlled in accordance with the received sequence.
